BY *Allen & Allen*
ATTORNEYS.

UNITED STATES PATENT OFFICE.

GEORGE STIEGLER, OF CINCINNATI, OHIO.

WATCH-CHAIN HOLDER.

Application filed December 1, 1922. Serial No. 604,290.

To all whom it may concern:

Be it known that I, GEORGE STIEGLER, a citizen of the United States, and a resident of Cincinnati, in the county of Hamilton and State of Ohio, have invented certain new and useful Improvements in Watch-Chain Holders, of which the following is a full, clear, and exact description, reference being had to the accompanying drawings, forming part of this specification.

My invention relates to devices for holding the cross bar usually found on a watch chain, firmly to the wearer, and is particularly adapted for use with trouser belts.

Most men now wear belts to hold up their trousers in the summer time, and no vest, and as a result, have no place to attach their watch chain. This results in danger of the watch falling out of the pocket and onto the ground, and also makes it fairly easy for a pickpocket to remove the watch without cutting the chain.

It is the object of my invention to provide a simple device, which may be made part of the belt or attached to the belt or trousers hem or elsewhere, which will act to hold the watch chain cross bar firmly against dislodgment.

Among other things I prefer to form the device so as to provide a central aperture through which the chain extends, and two lateral apertures through which the ends of the cross bar will protrude. This form necessitates a freedom for thrusting the cross bar edgewise through the central aperture, and thus to dislodge the bar will require a motion which cannot be accomplished with the clothing impeding the withdrawal action. Other forms may, however, be adapted to the same end, although not so effectively, and I show my preferred form as illustrative of the principles involved.

I thus accomplish my object by that certain construction and arrangement of parts to be hereinafter more specifically pointed out and claimed.

In the drawings:

Figure 1 is a front elevation of a belt showing my device in the form of a grommet in the belt.

Figure 2 is a perspective broken away to show a central vertical section taken through a belt showing the device in the same relation thereto as in Figure 1.

Figure 3 is a perspective view of the device used with a gripping device. 55

Figure 4 is a side elevation of the device shown in Figure 3.

A watch chain is shown in Figure 1 in dotted lines at 1, with the cross bar 2 also dotted in. The device in Figure 1 is shown as mounted in a belt 3. The belt is pierced with an oval-shaped hole into which is placed an oval-shaped grommet having the curved outer rim 4 and the flange 5, which is thrust through the hole and forced out laterally to engage the inner face of the belt, as shown in Figure 2.

At two points intermediate the ends of the grommet are formed, as part of the single piece, the curved arms or cross bars 6, 6. These two arms leave a central space 7 between them, and two lateral spaces 8, 8. They are elevated at the center so as to lie outside of the plane of the grommet. 75

A watch chain cross bar in such a device is thrust endwise through the central hole 7 until it has entirely passed through the hole. One end of the chain bar is then brought out through one of the apertures 8 and 80 pulled laterally far enough for the other end to slip out through the other aperture 8. The chain is then pulled tight and this draws the cross bar into a centered position as shown in the dotted lines of Figure 1. 85

The bar cannot be dislodged from this position without reversing the steps above described, so that without the co-operation of the wearer it will be next to impossible to get the watch chain out of the grommet device without cutting or breaking it. 90

The position of the grommet in the belt will preferably be such as to co-operate most conveniently with the usual placing of the watch pocket, i. e. to the right of the trousers fly. 95

In Figures 3 and 4 I have illustrated another form of device in which the member 10 corresponds to the portion 4. The cross arm 11 corresponds to the arm 6, 6, and the apertures left are the same as in the first two views. 100

In this instance, however, I have secured to the upper edge of the portion 10 a clip having an arm 12 and return bent portion 13 105 and a resilient curved tongue 14 of spring metal set inside of the curve of the hook. An L-shaped member hinged at 15 and hav-

ing an arm 16 and a short arm 17 acts, when laid flat with the outer portion of the hook, to thrust inwardly the tongue 14, thereby grasping the face of a belt, trousers waist-band or other article of clothing.

As this form of clip is a well known article of commerce, and not of my invention, I do not believe that further detailed description is required of it. Any form of device for attaching the oval-shaped member will serve so long as it leaves it free enough to permit the watch chain cross bar to be set in place and removed in the manner described.

It will be noted that both devices are of extreme simplicity, and yet due to the fact that they require a certain method of insertion and removal of the cross bar, act, in co-operation with the body and other garments of the wearer, to prevent dislodgment of the cross bar, once it is mounted, since it must be turned endwise to be withdrawn, which can only be done when the belt is loose from the body or the clothing is loose behind the clipped-on structure.

Having thus described several structures embodying the features of my invention, what I claim as new and desire to secure by Letters Patent, is:—

1. In a device of the character described, the combination with a trousers belt or the

like, same having a hole formed therein of sufficient size to permit the insertion of the cross bar of a watch chain, of a grommet surrounding and reinforcing said hole, said grommet having a pair of interspaced elevated arms extending across the aperture therein, for the purpose described.

2. A device for securing the cross bar of a watch chain, comprising a plate having a rim surrounding an opening, and a pair of interspaced arms extending across said opening from the rim, said arms being elevated above the plate sufficiently to permit such cross bar to lie on the face of the plate and beneath the two arms, with the chain extending out between the bars.

3. A device for securing the cross bar of a watch chain, comprising a plate having a rim surrounding an opening, and a pair of interspaced arms extending across said opening from the rim, said arms being elevated above the plate sufficiently to permit such cross bar to lie on the face of the plate and beneath the two arms, with the chain extending out between the bars, and means for mounting said device on a garment in such a position as to be backed up when in use on the wearer so as to prevent endwise movement of the cross bar through the opening between the cross arms.

GEORGE STIEGLER.
